UNITED STATES PATENT OFFICE

2,347,905

WASTE WATER HUMIDIFIER

Howard B. Halt, Philadelphia, Pa.

Application September 3, 1943, Serial No. 501,063

2 Claims. (Cl. 62—141)

My invention relates to humidifying air and relates particularly to utilizing a water cooler to humidify the air in a room wherein the water cooler is placed.

Water coolers of the type for cooling water contained in five gallon bottles wherein refrigerating systems are operated by electricity are common and they employ an electric motor which drives a compressor as well as a fan for cooling the refrigerant. In the prior art water coolers of the water bottle type the waste water dropped into a container that was removably attached to the water cooler, and the waste-water container had to be emptied when it became filled to prevent overflow, or it was cleaned each night as a routine duty.

It is an object of my invention to provide a water-bottle cooler with a device whereby the waste water need not be physically removed from its container.

Another object of my invention is to provide a water cooler wherein the motor fan will evaporate the waste-water to humidify the air.

Another object of my invention is to provide in a water cooler of either the bottle type or of the city pressure supply type an air humidifying device.

Another object of my invention is to provide a positive preventer of water overflow from a water-bottle cooler.

Other objects of my invention are to provide an improved device of the character described of simple and economical construction, that possesses a maximum amount of serviceability and of strength.

With the above and related objects in view, my invention consists in the details of construction and combination of parts, that will be herein after fully described and the description will be more readily understood when it is read in conjunction with the accompanying drawings in which:

Fig. 1 is a side elevational view partly broken away of a bottle type of electric water cooler embodying my invention.

Fig. 2 is a fragmentary front elevational view of a series of waste water trays adapted to be suspended from the rear of the water cooler and adjacent the motor fan.

Fig. 3 is a sectional view taken on the lines 50 3—3 of Fig. 2.

Fig. 4 shows a modification of my invention as employed in a city pressure water supply cooler, partly drawn in broken away fashion to show the interior details.

Referring now in detail to the drawings wherein my invention is illustrated, I show in Fig. 1 a water cooler of the bottle type wherein a frame, generally designated as A, supports a bottle, generally designated as B, wherein water is held; a reservoir, generally designated as C, retains the water which emerges from bottle B, and the reservoir C is surrounded by coils, generally designated as D, which retain the refrigerant to provide a heat exchange unit.

Within the frame A is an alcove, generally designated as E, which has a faucet, generally designated as F protruding therein. Within the alcove E is a waste water drain generally designated as G, to which a waste pipe 10 is connected. The waste pipe 10 carries the waste water to a plurality of trays, generally designated as H, which are suspended adjacent the lower end of the rear side of the frame behind condenser coils, generally designated as J. An electric motor, generally designated as K, suitably supported within the cooler frame carries a compressor driving belt as well as fan blades or vanes 12, so that the rotation of the vanes 12 blow or agitate the air adjacent thereto to cool the condenser coils J and to blow over the trays H. The air agitated over the trays H vaporizes the water therein so that the water vapor is carried away by the agitated air thus humidifying the air in the room.

The trays H comprise a plurality of vertically arranged trays 16, 18, 20, 22 and 24 which receive drain water from drain pipe 10 and the trays are spaced one from the other. Each of the trays is slightly less in width than the width of the frame A so that the trays cannot be seen from the front side. The trays are narrow in width in order that the cooler will not extend unnecessarily far from the wall, adjacent which the cooler is placed.

Each of the trays 16, 18, 20, 22 has an overflow pipe 23 therein in order that the overflow of waste water will not travel over the sides of the tray upon the floor, so that damage or messiness 45 of the floor is prevented.

The last or bottommost tray 24 is connected to one end of an air pipe 26 and the other end 28 of the air pipe 26 opens into the uppermost end of the reservoir water retaining chamber C, where no water but air fills the upper space. The purpose of the air pipe 26 is to permit air to enter the reservoir C in order to enable the air to displace the water drawn from the bottle—otherwise a vacuum exists. However, when the bottom tray 24 is filled with water the air pipe 26

is closed to the atmosphere and no water will drain from the water bottle because the air pressure within and outside of the water bottle is not equalized. When the condition aforementioned occurs, to wit: no water can be drawn from the faucet F, it should be expedient to remove and drain plurality of trays in order to prevent overflow of the water. However, under normal conditions of operation the drain water will be evaporated long before it reaches the lower evaporator tray 24. Hence, it can be recognized that under normal conditions of operation the bottle type water cooler embodying my invention need not have the drain water removed, as the drain water is vaporized to humidify the air of the room—particularly during the winter months when air is exceptionally dry. It should be noted that a resilient ring 30 on which the bottle B rests completely isolates the water reservoir C from the atmosphere when the bottle 20 B of water is inverted and laid thereon.

Referring now to another embodiment of my invention illustrated in Fig. 4 I show a water cooler, generally designated as A1, of the electric refrigeration type wherein the water is received from the city water supply system. The water fed from the city pressure supply system through pipe 32 enters a water reservoir C1 where the water is chilled by the cooling or refrigerating coils D1. The drain or waste water passes through a drain water pipe 34 which terminates in the top of one of the humidifying trays 36. The drain water collects in each of the trays 36, so that the fan blades or vanes attached to an electric motor, generally designated as K1, when 25 rotating agitate or fan the air over a condenser coil generally designated as J1, and the trays 36

thereby cooling the condenser coils J1 and vaporizing the water in the trays 36. A drain pipe 40 is suitably connected to the city waste water system because the amount of water used in the fountain type of city pressure water cooler is too large to be vaporized by the motor K1. Hence, the air in the room will be humidified by the fan 38 vaporizing the waste water.

Although my invention has been described in considerable detail, such description is intended as illustrative rather than limiting, since the invention may be variously embodied, and the scope of the invention is to be determined as claimed.

I claim as my invention:

1. In combination with a water-bottle water cooler, a humidifying tray for retaining waste water of the cooler, and means common to both the cooler and the humidifying tray whereby the waste water in the trays will be vaporized; a water reservoir within said water cooler, and means connected to said reservoir and said humidifying trays whereby the flow of water from the reservoir will be controlled by the amount of water in the humidifying trays.

2. In combination a water cooler having a built-in non-removable waste drain line, a removable waste water air humidifier, means to attach said humidifier adjacent the rear portion of said water cooler, said water cooler having condenser coils and a fan to blow air over said coils, and said air humidifier being supplied by water from the waste water drain, said humidifier being located adjacent said condenser so that the same agitated air passes over the humidifier and the condenser.

HOWARD B. HAIT.
